CLAIM

The ornamental design for a circular saw base plate as shown and described.

DESCRIPTION

FIG. 1 is a front perspective view of a circular saw base plate in accordance with an embodiment of the present invention.

FIG. 2 is a left-side view of the circular saw base plate of FIG. 1.

FIG. 3 is a right-side view of the circular saw base plate of FIG. 1.

FIG. 4 is a front view of the circular saw base plate of FIG. 1.

FIG. 5 is a rear view of the circular saw base plate of FIG. 1.

FIG. 6 is a top view of the circular saw base plate of FIG. 1.

FIG. 7 is a bottom view of the circular saw base plate of FIG. 1.

FIG. 8 is a front perspective view of a circular saw base plate in accordance with yet another embodiment of the present invention.

FIG. 9 is a left-side view of the circular saw base plate of FIG. 8.

FIG. 10 is a right-side view of the circular saw base plate of FIG. 8.

FIG. 11 is a front view of the circular saw base plate of FIG. 8.

FIG. 12 is a rear view of the circular saw base plate of FIG. 8.

FIG. 13 is a top view of the circular saw base plate of FIG. 8; and,

FIG. 14 is a bottom view of the circular saw base plate of FIG. 8.

(Continued)

The portions of the circular saw base plate shown in broken lines are included for the purpose of illustrating environment and form no part of the claimed design.
